[57] CLAIM

The ornamental design for a combined toy mechanical gripping arm and detachable claw unit, as shown and described.

DESCRIPTION

FIG. 1 is a bottom plan view of a combined toy mechanical gripping arm and detachable claw unit showing our new design;

FIG. 2 is a bottom plan view of the detachable claw unit shown separately for clarity of illustration;

FIG. 3 is a front elevational view thereof, with the detachable claw unit mounted to the arm;

FIG. 4 is a left side elevational view thereof, with the detachable claw unit mounted to the arm;

FIG. 5 is a top plan view of the detachable claw unit;

FIG. 6 is a top plan view thereof, with the detachable claw unit removed from the arm;

FIG. 7 is a top plan view thereof, with the detachable claw unit mounted to the arm;

FIG. 8 is a right side elevational view thereof, with the detachable claw unit mounted to the arm; and,

FIG. 9 is a perspective view thereof, with the detachable claw unit mounted to the arm.
